FERRIS WHEEL FOR CHILDREN

Ralph Hotkins and Charles Shankman, New York, N.Y.,
assignors to Capitol Projector Corporation, New York,
N.Y., a corporation of New York

Application April 30, 1959, Serial No. 55,717

Term of patent 14 years

(Cl. D34—5)

Figure 1 is a front view in perspective of the Ferris wheel for children, showing our new design.

Figure 2 is a front elevational view slightly reduced in scale.

Figure 3 is a side elevational view slightly reduced in scale.

Figure 4 is a rear elevational view further reduced in scale.

We claim:

The ornamental design for a Ferris wheel for children, as shown.
